DEMOUNTABLE TRUCK BODY

Louis Delivuk, Spokane, Wash.

Application December 16, 1940, Serial No. 370,260

10 Claims. (Cl. 298—27)

The object of this invention is to provide a self-contained, demountable, quick discharging grain body for trucks.

Farmers employ a single truck in many capacities and hence special and various types of bodies are required for each use. A very special capacity is the hauling of grain from the combine in the field to the elevator, and a truck body for this purpose must meet special requirements among which is the ability of the body quickly to discharge its contents at the elevator without the delay incident to sweeping or shoveling out quantities of grain that has not been discharged. Congestion of traffic approaching an elevator during busy seasons has long been an acute problem which it is one of the objects of this invention to solve by providing a truck body in which a rapid and complete discharge of all its contents can be quickly accomplished.

A further object is to provide a truck body that may be demountably and very securely connected with the frame of any modern truck without drilling or in any way altering the truck frame, and since modern trucks include portions disposed in a position to obstruct a gravity discharge of grain, it is a feature of this invention to provide a body having discharging portions that will avoid any obstructing portions of the running gear or frame of the truck, and which will, at the same time, afford a maximum efficiency for quick discharge.

Because of the extensive use of trucks in entering and leaving the harvest fields, which are frequently hilly, and to obtain a maximum capacity and also lower the center of mass or gravity as far as possible, it is a feature of this invention to extend the body as far as possible below the top of the frame on which it is demountably secured, thereby preserving equilibrium and stabilization as much as possible.

Because of the low locations of the discharging portions of the body with respect to the frame, it is a feature of this invention to provide a novel type of operating mechanism which is located below the frame, for the purpose of controlling discharge, and this mechanism is provided with a detachable section to permit removal of the body from the truck frame.

The invention has many other objects and features which will be more fully described in the following specification and which will be more particularly pointed out in and by the appended claims.

In the drawings:

Fig. 1 is a longitudinal vertical sectional view 55

of one form of my improved body illustrating the working position it would assume on a truck frame, the latter being shown partly in section and partly in elevation.

Fig. 2 is a plan view of a portion of a truck frame and a part of the running gear, on a reduced scale.

Fig. 3 is a view in side elevation of the body and a portion of the truck frame showing the same on a slightly reduced scale.

Fig. 4 is a sectional view on an enlarged scale taken on line 4—4 of Fig. 1, showing the front discharge opening and looking to the right of Fig. 1.

Fig. 5 is a view on the same scale as Fig. 4, and is a longitudinal sectional view through the rear discharge opening.

Fig. 6 is a sectional view taken on line 6—6 of Fig. 1.

Fig. 7 is a plan view of the improved closures or gates for the discharge openings and the connecting rods therefor.

Fig. 8 is an edge view thereof.

Fig. 9 is a sectional view on line 9—9 of Fig. 5.

Fig. 10 is a view in elevation of a frictional clamping device looking in the direction of arrow 10, of Fig. 4.

Fig. 11 is a sectional view on line 11—11 of Fig. 5.

Fig. 12 is a face view of one of the supporting shoes with the clamping bolts omitted.

Fig. 13 is a sectional view on line 13—13 of Fig. 12.

Fig. 14 is a diagrammatic end view of the truck body with details omitted.

Like characters of reference designate similar parts throughout the different figures of the drawings.

I will first briefly describe a conventional form 40 of truck on which my improved grain body is disposed, with special reference to Figs. 1, 2 and 3.

The spring supported frame comprises longitudinal frame members 1, which are reduced in vertical thickness at 2, throughout the rear portion of the length thereof. The longitudinal members 1 are shown braced by transverse frame members 3 and 4, and the frame is supported by springs 5 on rear axle 6, the rear wheels being indicated at 7 and the front wheels at 8. The differential casing is shown at 9 and its shaft, which extends forwardly to the change speed gear (not shown), is indicated at 10. Because of the fact that the frame is spring supported it will be clear that a portion of the running gear, which may be the casing 9, will take various

positions relative to the frame. I have very generally indicated the cab at 11.

Reference will next be made to the truck body, which constitutes the major portion of this invention.

Said body has a front wall 11 which is shown to be vertically disposed or upright, and the lower portion 12 thereof is inclined to form a hopper section, the purpose of which will be later described. A rear wall is indicated at 13, and the same is vertical and has near its lower end an inclined hopper section 14. Said body is provided with side walls which are of uniform construction and to which the same reference numerals will be applied, and as shown, particularly in Fig. 14, the upper portions of the side walls are parallel and upright and are indicated at 15, and are spaced apart to such an extent, with respect to the width of the truck frame, as to substantially overhang said frame laterally thereof. The lower portions of said side walls converge inwardly to form hopper sections, the upper portions having an inclination indicated at 16 and the lower portions having an inclination indicated at 17. The lower edges of said walls are indicated at 18, and it is important to note that these hopper sections extend substantially below the plane on which the body is supported on the truck frame, as will later appear. It may also be stated that the different angles of inclination are not essential to this invention although they are advantageous in affording the greatest possible height for the upright sides and the widest spacing of the hopper sections below the tops of the longitudinal frame members 1. Further, the hopper units 16, which are more nearly horizontal than the units 17, serve to sustain a relatively greater portion of the weight of the load, while the units 17 serve to facilitate quick discharge of the grain.

However, it is more important to note that the inclination of both units 16 and 17 are, in practice, at least thirty degrees or more, since the inclination of repose of grain is less than this degree, and by employing this degree of inclination there is absolute assurance that the grain will descend by gravity without leaving any undischarged portion. However, in an abundance of caution, I prefer to cover the inner face of the hopper portions 16 and 17 with a smooth metal such as sheet iron or other suitable material, as shown at 19. Because the angle of repose of grain varies somewhat with respect to the degree of dampness, and also to the dirt content of the grain, as well as other factors, I have demonstrated that by establishing a minimum angle of thirty degrees, and covering the same, I am assured of the most effective possible gravity discharge.

Reference will next be made to the manner in which the truck body is stiffened so that it can be made of wood or other comparatively light weight material.

I employ vertically disposed stays suitably distributed along the sides of said body and which preferably extend to the full height of said body, and as all of said stays are alike in form and function, only one need be described in detail.

As shown, six full length or main stays are provided on each side of said body and are generally indicated at 20. I prefer to employ metal stays, and in the present construction I have shown the stays formed of channel iron or steel with the webs 21 thereof disposed in abutting relation against the exterior of the sides and 75

secured thereto in any desired manner as by means of bolts or screws 22, the flanges 23 projecting outwardly. Said channel stays are shaped to conform to the shape of the sides, as shown, 5 for instance in Fig. 4, and they terminate at their lower ends at 24 in substantially flush relation with the bottom edge 18 of the sides, and hence they strengthen the body throughout its height and constitute an effective means for also 10 taking the major load stresses, as will presently appear. It is very important to relieve the body, as far as possible, from these load stresses and provide a frame work to take such stresses because trucks carrying grain not only traverse the 15 rough terrain of harvest fields but also equally rough roads.

Reference will next be made to the manner in which the truck body is demountably mounted on the truck frame.

Each of said stays is provided with means for engaging the truck frame which functions not only to support the truck body, but which also serves to maintain the latter against shifting movement laterally or longitudinally of the truck frame.

As all the body supporting devices are alike in form and function, only one need be described in detail.

Reference is made to Figs. 4, 6, 12 and 13, in which I have shown a stay provided with a shoe formed of angle iron or steel in which one flange or limb is substantially horizontally disposed as indicated at 25, for engagement with the top of truck frame member 1. This flange 25 is of a length to extend laterally of the flanges 23 to form clamping ends 26, and I preferably, although not necessarily, turn up the end edges as shown at 27. The remaining flange 28 is substantially vertically disposed and is adapted 30 for engagement with an inside face of truck frame member 1 to stabilize the truck body against a lateral movement. As shown, the truck members 1, and the reduced portions 2 thereof, are formed of channel steel with the webs thereof 35 disposed outwardly and the flanges inwardly in the usual manner, and it will be seen that the flange 28 of the shoe engages the inner edge of the upper flange of said truck frame channel.

Reference will next be made to the manner in which the shoes are secured to the stays.

As shown, the flanges 23 are recessed to conform to the angular shape of the elbow or bight 29 of the shoe, and the latter is preferably welded to the recesses in said channel stay, and as a further anchorage I prefer to spot weld the elbow to the web 21 and the inner faces of the channel flanges 23, as indicated at 30. Thus, the shoe is rigidly secured to the stay, although it will be understood I do not wish to be limited to this particular manner of anchoring the shoe to the stay.

As thus far described, it will be clear how the truck body can be supported by these shoes, one of which is provided for each stay, but this kind of support would not prevent longitudinal sliding movement of the body on the truck frame. Therefore, I will next describe my novel means for frictionally clamping the body onto the truck frame and effectively preventing its longitudinal movement thereon without in any way drilling or altering the truck frame.

Referring to Fig. 4, for instance, my improved clamping device, which of course is incorporated with the shoe, specifically involves a pair of U-bolts. The bights 31 of said bolts seat on said

clamping ends 26, and the turned-up edges 27 serve to hold said bights in position. The limbs 32 extend downwardly along the sides of the truck frame members 1-2 and pass through suitable openings 33 in a gusset plate 34 extending across the lower flange of the frame member 1-2, and nuts 35 are threaded on the ends of said bolts and when tightened serve to frictionally hold the shoe in a very secure manner to the truck frame. Because of the lengthwise engagement of the shoe with the truck frame member 1-2, any tendency of the body to slide lengthwise of the truck frame would impose a binding action on this clamping device which would render the latter highly effective in resisting such sliding movement. It will be seen that the U-bolts must be longer where they coact with the enlarged frame members 1 than where they coact with the reduced portions 2, but otherwise all the clamping devices are identical in form and function.

Reference will next be made to the manner and means for strengthening the body at an intermediate portion of its length.

It may be stated that the bottom 18 of the side walls is at the same level throughout the length of said walls, but because of the transverse truck frame members 3 and 4, it is necessary to recess the side walls as indicated at 36 and 37. To a certain extent these recesses serve to weaken the side walls of the body and to strengthen the body at these locations, namely, the locations of the recessed portions I provide relatively short stays 38 and 39, which are identical in form and function, hence only one need be described in detail. These stays, as shown in Fig. 3, only extend from the bottom edge 18 to a point slightly abreast of the upright sides 15, and may be formed of channel iron or steel and secured to the exterior of the sides of the body by any suitable means such as screws 40, which may extend through the webs 41 into the sides of the body. The flanges 42 project laterally of the body, as shown. Shoes are provided, only one of which need be described as they are identical in form and function, and said shoe consists of an angle iron or steel having a horizontally disposed flange 43 adapted to rest in frame member 1, and a vertical flange 44, adapted to engage the inner face of member 1. This shoe is welded to stay 39 in the same manner as the shoes of the main stays, heretofore described, and I have shown in Fig. 6 the bight or elbow spot welded at 45.

In order to brace this portion of the truck body, I utilize these short pairs of stays for the purpose of disposing a cross tie, and in Fig. 6, I have shown a cross tie strip of metal 45' extending across the open body and having its ends 46 secured to the webs 41, of said short stays by means such as screws 47. Each pair of short stays will be thus equipped and this disposition of the cross stays 45' will not impede discharge of grain from said body because they are disposed at a bottom of the body point through which grain is not discharged, as will presently appear.

Because of the fact that my improved body completely discharges its content of grain, it is possible to brace the body in a manner which I will next describe.

The front and rear walls may be provided with one or more channel irons 48 and 49, respectively, and I have shown longitudinal braces or brace rods 50 and 51, adapted to extend through said front and rear walls and their channel irons, and be secured by nuts 52 and 53. Said rods take their stresses in tension, and I have provided

each thereof with a sleeve 54 and 55, respectively, which sleeves abut against suitable washers 56 and 57 interposed between the ends of said sleeves and said front and rear walls 11 and 13, respectively. These sleeves take their stresses in compression, and it will now be clear that when the nuts 52 and 53 are tightened the opposite walls will be sustained very rigidly in fixed spaced relation. I have also shown transverse braces of the same type, in which the rods are indicated at 58 and the sleeves at 59, as to the upper pair, the lower pair being indicated by 60 for the rods and 61 for the sleeves. Of course it will be understood that the rods will extend through the webs of the main flanged stays 20, and be provided with nuts 62 and 63, and that the said transverse braces will be identical with the heretofore described longitudinal braces in all respects, whereby the body will be effectively braced against all types of stresses, both inwardly and outwardly, in line with said braces.

Reference will next be made to the bottom structure of the body and to the manner in which I insure complete gravity discharge of all the contents of the body.

Said bottom structure has a plurality of bottom discharge sections extending below the plane of engagement of said shoes with the truck frame members 1-2, which, in this particular form of the invention, consists of a front and a rear bottom discharge section. Said bottom structure also has an intermediate section which not only spans or bridges the transverse frame members 3 and 4, and forms a clearance space x for downward movement of the body when loaded, or upward movement of the differential 9, but which additionally performs a gravity discharge for the grain toward said front and rear discharge sections.

It will be seen that the front hopper or grain guiding plane section 12 and the like rear section 14 extend downwardly to the common lower edge plane 18, at which the converging sections of the side walls 11 terminate, and this elevation is below the plane of supporting engagement of the shoes with the longitudinal frame members 1-2 of the truck frame. Of course the sections 12 and 14 juncture laterally with the sections 16 and 17, to form a continuous causeway hopper leading downwardly to the discharge openings A and B. Thus, the front section 12 leads to the front side of the front opening A, the section 14 leads to the rear side of the rear opening B, and the converging sections lead to the lateral sides of said openings, the latter being shown of rectangular form.

The intermediate section is shown in the form of an inverted V, and has a grain guiding hopper section 64 formed by one limb, and which extends downwardly from the linear apex 65, to the rear side of the front opening A, and a similar section 66 which extends downwardly from the apex 65 to the front side of the rear discharge opening B. Of course sections 64 and 66 juncture laterally with the converging sections 16 and 17, so that both openings A and B, will be surrounded by hoppers leading all the grain content toward the discharge openings A and B, by gravity.

It will now be clear how the intermediate section not only spans the transverse members 3 and 4, but forms a clearance area x for downward movement of the body, or upward movement of the differential casing 9, and also permits of a disposition of the tie straps 45 in such a position that they cannot obstruct the discharge of grain.

I have also shown these hopper sections covered

with thin material such as sheet metal, as indicated at 14' and 60'. This facing has been omitted in Fig. 1 because of the small scale at which it would have to be shown.

Reference will next be made to the closures or gates for controlling discharge of the grain from said body.

The discharge opening A is provided with a gate frame comprising front and rear sides 67 and 68 (Fig. 1) and lateral sides 69 (Fig. 4), and to the bottom of this frame are attached gate guides 70 which are recessed at 71 to form, together with the bottom of sides 69, a guide-way for slidably supporting a closure or gate 72, which may be formed of thin steel or the like. As shown in Fig. 7, the guides 70 (only one shown) are long enough to permit of slidable movement of the gate far enough to uncover opening A and still retain the gate 72 in coactive relation with said guide. It will also be seen from Fig. 1 that this gate 72 is disposed below the transverse frame members 3 and 4 of the truck frame.

The opening B is likewise provided with a gate frame (Figs. 5 and 11) which is in horizontal alignment with the gate frame of opening A, and which consists of front and rear sides 73 and 74, and lateral sides 75. Gate guides 76, recessed at 77, are secured to the lateral sides 75 for guiding a rear gate 78.

Reference will next be made to the improved means for operating said gates in unison as this is greatly preferable to individual operation thereof although the latter is not outside the scope of this invention.

As shown, gate operating bars 79 (Figs. 1 and 4) are rigidly secured to the bottom of gate 72, and bars 80, which are provided with rack teeth, are secured rigidly to the bottom of gate 78. The bars 79 and 80 are detachably connected by intermediate bar sections 81 by screws 82', as illustrated in Fig. 5, or in any other desired manner.

The importance of this detachable connection resides in the fact that the sections 81 are of a length at least equal to the spacing of frame members 3 and 4, so that said sections 81 can be detached when it is desired to dispose the truck body onto the frame of the truck, and then connected up, or detached when it is desired to remove the body from the truck. This being desirable because the bars are below the frame members 3 and 4. However, even though the sections 81 were of less length than the spacing of members 3 and 4, this feature would meet the operative requirements of the invention since the gates 72 and 78 could be adjusted endwise to permit the demountable body to be put on and taken off the truck frame, respectively.

Reference will next be made to the manner of operating the gates.

A shaft 82 (Figs. 1, 4 and 11) is journalled in bearings 83 (one only being shown) and said shaft extends transversely across the truck frame near the rear thereof and is provided with an operating crank 84, which, in practice will be disposed in a clearly accessible position at one side of the truck, preferably at the left hand side thereof. In order to avoid drilling the truck frame and for the purpose of obtaining effective demountable support for the shaft 82, I provide gusset plates 85 on the rearmost clamping devices that are formed integral with the bearings 83.

Said shaft 82 is provided with gears 86, meshing with the teeth of rack rods 80 so that when the crank 84 is turned the gates 72 and 78 will be shifted in unison into and out of discharging

positions with respect to the openings A and B.

In Fig. 9 I have shown how the side and end walls 15 and 13, respectively, may be connected up through the rearmost stay 20. A vertical beam 87 is shown secured to the stay by bolts 88 extending through said beam and through the web 21 of the stay, and of course the rear wall 13 can be nailed or otherwise secured to said beam 87.

10 It is believed that the operation of the device of my invention will be clear from the foregoing but I will very briefly recapitulate the same as follows:

In mounting the body the bar sections 81 15 will be detached, and the body will be deposited on the truck frame by a crane or otherwise into the position shown in Fig. 1. Then the sections 81 will be connected up and the crank 84 will be turned to close the gates 72 and 78, whereupon 20 the body will be ready to receive a load of grain.

When the truck reaches an elevator the crank 84 will be turned to shift the gates 72 and 78 in unison into an open position, and the grain will 25 all discharge through said openings A and B, as will now be clear.

Because grain is hauled from the harvest field over rough ground and often over rough roads, it is important to establish and sustain equilibrium as far as possible, and the fact that the discharge 30 sections A and B extend so far below the plane of engagement of the shoes with the truck frame, I greatly increase stabilization of the loaded truck.

It will be clear that since the entire weight of 35 the body is taken by the stays 20, to which the body is secured, said stays constitute, with the cross ties, a rigid frame that not only very greatly strengthens the body and permits of relatively light weight material being used, but this frame 40 also takes the major load stresses by reason of the fact that the load stresses are directly transmitted from the shoes to the stays, instead of to the body, and a feature of very great importance in this respect is that the main stays 20 are vertically disposed.

In traversing a rough terrain, the loaded truck 45 body is not only subjected to spreading stresses, especially laterally, but in making turns, as well as in traversing ruts, the truck body is subjected to torsional stresses, all of which it is the purpose of this invention to resist and overcome, without resorting to excessive weight.

By using a plurality of vertical stays on each 50 side of the body, together with the cross ties traversing the interior of the body, I can not only make the body of relatively lighter weight material, but I can also use main stays of lighter weight, and this is a feature of great importance.

It will also be seen that the grain body is entirely self-contained, both as regards its fixed 55 portions and its operating portions, hence it can be demountably secured to a truck without in any way altering or drilling the same.

It is believed that my invention will be clearly 60 understood from the foregoing description, and while I have herein shown and described one specific form thereof, I do not wish to be limited thereto except for such limitations as the claims may import.

I claim:

1. In a demountable quick discharging grain 65 truck body structure for a truck having longitudinal and transverse frame members, a truck body having upright sides laterally overhanging the truck frame and provided with inwardly

converging hopper sections extending downwardly from said sides and the lower portions thereof extending between the longitudinal frame members, shoes fixed to said hopper sections for engaging the longitudinal frame members for removably supporting said body thereon, said body having a bottom provided with a rectangular front discharge opening disposed forwardly of said transverse frame members and a rectangular rear discharge opening disposed rearwardly of said transverse frame members and said hopper sections extending to the lateral sides of said front and rear openings, said bottom also comprising a transversely disposed grain guiding unit of inverted V-form longitudinally spanning said transverse frame members and laterally jutting with said hopper sections and having one plane section extending forwardly and downwardly to the rear side of said front discharge opening and the remaining plane section extending rearwardly and downwardly to the front side of said rear opening, and said bottom having an inclined plane section extending rearwardly and downwardly to the front side of said front opening and a plane section extending forwardly and downwardly to the rear side of said rear opening, whereby the entire lower area of said body will slope toward and discharge toward said openings for quick and complete egress of the contents, and means for controlling egress through said discharge openings.

2. In a demountable grain truck body structure for a truck having longitudinal frame members, a truck body for grain having upright sides laterally overhanging the truck frame and the lower portions of said sides converging inwardly to form hopper sections and being proportioned to be disposed between the frame members, a plurality of vertically disposed stays of channel iron secured to the exterior of said sides in suitable spaced relation and shaped to the contour of said sides and hopper sections to stiffen said body and take the load stress, and certain of said stays each having a shoe of angle iron fixed to the flanges thereof with one flange of the shoe engaging the top of the frame member and the remaining flange of the shoe engaging an inner face of the frame member to respectively support and laterally stabilize said body on the frame.

3. In a demountable grain truck body structure for a truck having longitudinal frame members, a truck body for grain having upright sides laterally overhanging the truck frame members and the lower portions of said sides converging inwardly to form hopper sections and being proportioned to be disposed inwardly between said frame members, a plurality of vertically disposed stays of channel iron shaped to conform to the contour of and secured to the exterior of said sides to stiffen said body and take the load stress, and certain of said stays each having a shoe of angle iron rigidly fixed thereto with one flange of the shoe engaging the top of the frame member and having clamping ends extending laterally of its stay and the remaining flange of said shoe engaging an inner face of the frame member to respectively support and laterally stabilize said body on said frame, U-bolts having their bights engaging said clamping ends and their limbs extending downwardly on opposite sides of the frame member, and a gusset plate on the lower face of the frame member accommodating the ends of said limbs, and nuts on said limbs engag-

ing said gusset plate for frictionally clamping said shoe to the frame member.

4. In a demountable grain truck body structure for a truck having longitudinal frame members, a truck body for grain having upright sides laterally overhanging the truck frame members and the lower portions of said sides converging inwardly to form hopper sections and being proportioned to be disposed inwardly between the frame members, a plurality of vertically disposed metal stays shaped to conform to the contour of and secured to the exterior of said sides to stiffen said body and take the load stress, certain of said stays each having a shoe engaging the frame member, and means embracing the frame member for frictionally clamping the shoe to the frame member to hold said body against longitudinal or lateral movement with respect to the frame members.

20 5. In a grain truck body structure for a truck having a spring supported truck frame comprising longitudinal and transverse frame members and a running gear element movable upwardly relative to the frame between said transverse members, a grain truck body having supporting means for engagement with the frame, said body having bottom sections extending downwardly below the plane of supporting engagement of said means with the frame, one bottom section being 25 disposed forwardly and another rearwardly of said transverse members and each of said sections having a controlled discharge opening for grain, and that portion of said bottom directly above said transverse frame members and gear element being elevated to bridge said members and permit unobstructed upwardly movement of said element with respect to said frame.

6. In a grain truck body structure of the class described, a truck body having sides and ends 40 and provided with a relatively enlarged upper portion and said sides and ends being convergingly tapered at their lower portions and provided with controlled grain discharge openings, metal stays shaped to conform to and being secured to the exterior of said sides and ends to stiffen the body, tension rods extending lengthwise through said enlarged portion from end to end and being tensioned against certain of said stays, strut sleeves surrounding said rods and engaging said ends, and tension rods extending transversely of said enlarged portion and being tensioned against certain stays of the latter, and said last named rods each being surrounded by a strut sleeve engaging said sides.

55 7. In a demountable grain truck body structure for a truck having a frame composed of longitudinal and transverse frame members, a truck body having supporting means engaging the frame and provided with a bottom having an 60 intermediate section elevated to span the transverse frame members and provided with an front bottom section extending below said transverse frame members and disposed in advance thereof and a rear bottom section extending below said transverse frame members and disposed rearwardly thereof, each of said bottom sections having a discharge opening, a slidably mounted gate for controlling each opening, a rod disposed below said transverse members and rigidly connecting said gates to shift the same in unison and said rod extending to the rear of said body, and means at the rear of said body for imparting lengthwise movement to said rod to open or close said gates in unison, and said rod having a detachable section of a length substantially coex-

tensive with the spacing of said transverse members to permit of mounting and removal of said body to and from the frame, respectively.

8. In a demountable grain truck body structure for a truck having a frame composed of longitudinal and transverse frame members, a truck body having supporting means engaging the frame and provided with a bottom having an intermediate section elevated to span the transverse frame members and provided with a front bottom section extending below the tops of the transverse frame members and disposed in advance thereof and a rear bottom section extending below the tops of said transverse frame members and disposed rearwardly thereof, each of said bottom sections having a discharge opening, a closure for each opening, and mechanism disposed below said transverse frame members for operating said closures in unison, said mechanism having a detachable portion to permit of mounting and removing said body, respectively, onto and off from the frame.

9. In a demountable hopper truck body structure for a truck having longitudinal frame members, a truck body having upright sides laterally overhanging the truck frame and the lower portions of said sides converging inwardly to form

hopper sections and being proportioned to be disposed between the frame members, a plurality of vertically disposed stays secured to the exterior of said sides in suitable spaced relation and shaped to the contour of said sides and hopper sections to stiffen said body and take the load stress, certain of said stays each having a shoe fixed thereto for engagement with a frame member to support said body on the frame, and means for holding said shoes against lateral or longitudinal shifting movement on the frame members.

10. In a demountable hopper truck body structure for a truck having longitudinal frame members, a truck body having sides laterally overhanging the truck frame and the lower portions of said sides converging inwardly to form hopper sections and being proportioned to be disposed between the frame members, a plurality of vertically disposed stays secured to said sides and hopper sections to stiffen said body, and means secured to said stays for engagement with the frame members to support said body thereon, whereby the load stress will be sustained by said stays and means.

LOUIS DELIVUK.
